UNITED STATES PATENT OFFICE.

JOHN M. PECK, CORNELIUS VAN DYKE BENNETT, AND JAMES W. RYAN, OF LIMA, NEW YORK, ASSIGNEES TO THE PORCELAIN INSULATOR CORPORATION, OF LIMA, NEW YORK, A CORPORATION OF NEW YORK.

METHOD OF MAKING INSULATORS.

Application filed May 12, 1922. Serial No. 560,453.

To all whom it may concern:

Be it known that we, JOHN M. PECK, CORNELIUS VAN DYKE BENNETT, and JAMES W. RYAN, all citizens of the United States of America, residing at Lima, in the county of Livingston and State of New York, have invented certain new and useful Improvements in Methods of Making Insulators, of which the following is a specification.

10 The invention relates to the manufacture of sectional type insulators, wherein one section is arranged within another, as for instance in pin type insulators, and one of the chief purposes is to provide a structure

15 in which the several sections are held together rigidly, so as to effectually resist any strain or pressure that may ordinarily be imposed, and thus affording an insulator of highest efficiency.

20 A further object of the invention is to construct the sections of the insulator in such manner, and to secure them together by mechanism and according to a method that simplifies the manufacture and materially

25 reduces the final cost.

The improvements are applicable more especially to insulators of the type embodying two or more sections, each consisting of a hollow body portion closed at one end, a skirt portion, and a base portion extending beneath the skirt portion, and the method involves briefly the following steps:

First, forming the sections so that the bottom of the base portion of an outer section terminates somewhat above the top of the skirt portion of the adjacent inner section.

Second, forming a recess upon the inner surface of the side of the outer section adjacent to the base portion, so that the recess communicates with the space between the bottom of the base of the outer section and the top of the skirt of the adjacent inner section:

45 Third, placing a resilient filling cement or seal in the bottom or against the end wall of the outer section, and then nesting the inner section within the outer section, pressing them together tightly, and permitting the resilient seal to cool and harden.

Fourth, forcing a non-resilient cement, preferably under pressure, through the space between the sections and in the recess above mentioned.

The invention also includes other features, all of which will be clearly understood from the following description, when read in conjunction with the accompanying drawings, the novel features being pointed out in the claims following the specification.

In the drawings:

Figure 1 is a vertical sectional view of a pin type insulator, constructed in accordance with a preferred embodiment of the invention;

Figure 2 is a side elevation of a mechanism adapted for assembling the sections, and

Figure 3 is a sectional view, partially in elevation, of a mechanism which is used in forcing the non-resilient cement between the sections.

The invention can be applied to various forms of sectional insulators, and the disclosure of this application is intended merely to illustrate an example of different practical forms. In the construction shown, there are two sections designated generally at A and B, although the principles set forth are likewise applicable to insulators having three or more sections.

The sections are constructed with hollow body portions closed at one end as indicated at A' and B', and include skirt portions A² and B². The body portion of the section A terminates in a base portion A³, the section B being arranged for attachment directly to the supporting pin, as well known in this class of insulators.

The sections are formed with sufficient play between the side walls to permit the ready insertion of the inner section within the outer section, and it is desirable to prevent the non-resilient cement, that is used to secure the sections together, from coming in contact with the end of the section B, or a greater portion of the side walls than actually necessary to attach the sections.

To accomplish this, we employ a filling or sealing means, of some resilient material, as designated at A⁴. A successful material for this purpose is a resilient cement of an asphaltic nature, which may be poured into one section before nesting. The resilient cement, or seal A⁴, completely fills the space between the sections, preventing access of the non-resilient cement A⁵, and thus preventing the insulator from breaking under

- strains set up by expansion and contraction of cement between the sections, particularly at the corners A⁶, where great strain usually occurs.
- 5 In order to secure the sections together, the base portion A³ is formed so as to terminate somewhat above the top of the underlying skirt portions B², thereby affording the space α , and α' designates a recess or 10 pocket formed on the inner surface of the side of section A at a point adjacent to the base portion A³. The recess α' extends from the bottom of the base portion partially 15 along the side of the section, but only far enough to secure an efficient union. This leaves a substantial part of the space between the side walls of the sections filled with the resilient cement, or sealing means A⁴, resulting in a tight attachment between 20 the sections, while at the same time permitting expansion and contraction, and preventing destruction of the insulator, due to expansion strains across the space occupied by the resilient filler.
- 25 A suitable non-resilient cement is placed in the recess α' , preferably by forcing it in under pressure, and the walls of the recess may be grooved as indicated, or otherwise roughened, to cause the cementing medium 30 to adhere more firmly. The non-resilient cement, however, does not enter beyond the recess α' , being held against further movement between the sections by the seal A⁴.
- The preferred method of assembly is as 35 follows: the section A is placed in inverted position, and a small amount of hot, liquid, resilient cement, such as an asphaltic composition, is poured into its hollow interior, in sufficient amount to lightly cover the bottom thereof in a thin layer. The section B is then placed within the section A, and forced downwardly therein, preferably by 40 an apparatus such as illustrated in Figure 2, which serves to properly center the sections with reference to each other, and to enable readily applying the necessary pressure. As the sections are forced together, practically all of the resilient cement 45 is squeezed outwardly toward the side walls, and out of engagement with the end wall, and the space between the side walls as well as the curved corner portions A⁶ is thus filled by the resilient cement, as indicated at 50 A⁴ in Figure 1. Upon contact with the insulator sections, the cement just described quickly cools and hardens and forms an effective seal between the side walls of the sections. Thereafter, the sections are 55 attached together by a non-resilient cement that is forced, preferably under pressure, into the space between the pocket α' of the outer section and the opposite portion of the side wall of the inner section, the cement used in this instance being applied through 60 the space α between the sections, and pref- 65 erably by means of an apparatus such as shown in Figure 3.
- Referring now to Figure 2, C designates a stationary member that is recessed to receive the insulator section A when inverted, and C' is a vertically movable member that is recessed to receive the section B when inverted. The recesses in said members C and C' are arranged so as to insure proper centering of the sections, and an even spacing between the side walls thereof, so that the operator places the section A in the recess in the lower section C, and holds the section B lightly in the recess in the upper member C' as the latter is moved 70 downwardly under pressure. To effect this latter operation, the member C' is mounted on a vertical rod D, pivoted upon a lever E which in turn is pivoted to a standard E'. F is a spring which acts normally to 75 retain the rod D and member C' in uppermost position, as shown in Figure 2. F' is a controlling foot lever, and G is a connecting rod extending from the foot lever F' to the lever E, so that the operator, to 80 apply the necessary pressure between the sections after the resilient cement is poured into the outer section, depresses the foot lever F' against the action of spring F, and by holding the foot lever F' down for 85 an instant, sufficient pressure is applied to force the resilient cement outwardly between the side walls substantially as shown in Figure 1.
- To apply the non-resilient cement that 90 is used for the attachment of the sections, the insulator is placed in inverted position on a rotary table H in the manner shown in Figure 3, and one operator slowly turns the insulator and the table, while a second operator forces in the cement, by means of a hand device such as the common type of 95 grease gun, or any other convenient mechanism.
- Instead of using a cement as the sealing 100 means, we may employ any resilient filler to occupy the space between the sections beyond recess α' , and to prevent entrance of the non-resilient cement, and in this and other respects the invention is not limited to the precise construction or method of assembly set forth, but may be modified in 105 various ways without departing from the fundamental features of the improvements, and this application is intended to cover any changes or departures coming within the intended purposes of the invention or the scope of the following claims.
- We claim:
1. The method of constructing an insulator formed of a plurality of hollow porcelain sections, consisting of first placing a resilient cement within the outer section, nesting the sections and applying pressure thereto to squeeze the resilient cement out- 110
- 115
- 120
- 125
- 130

wardly and bring the sections close together, and then inserting a non-resilient cement through the space between the bottom edge of the outer section and adjacent surface 5 of the inner section, causing said non-resilient cement to fill the space between the sections not occupied by the resilient cement.

2. The method of constructing an insulator 10 formed of a plurality of hollow porcelain sections, consisting of first placing a resilient cement within the outer section, nesting the sections and maintaining an equal distance between the side walls there-

of while at the same time applying pressure 15 between the sections to squeeze the resilient cement outwardly and bring the sections close together, and then inserting a non-resilient cement through the space between the bottom edge of the outer section and 20 the adjacent surface of the inner section so that it fills the space between the sections not occupied by the resilient cement.

In witness whereof, we have hereunto signed our names.

JOHN M. PECK.

CORNELIUS VAN DYKE BENNETT.

JAMES W. RYAN.
